US00D361836S

United States Patent [19]

Engström

[11] Patent Number: Des. 361,836

[45] Date of Patent: ** Aug. 29, 1995

[54] **COMBINED EXTRACTION AND FEEDING ARTICULATED CONDUIT ARM UNIT FOR GAS**

[75] Inventor: **Hans T. Engström, Helsingborg, Sweden**

[73] Assignee: **AB Ph. Nederman & Co., Helsingborg, Sweden**

[**] Term: **14 Years**

[21] Appl. No.: **840,986**

[22] Filed: **Feb. 25, 1992**

[30] **Foreign Application Priority Data**

Aug. 26, 1991 [SE] Sweden 91-1669

[52] U.S. Cl. **D23/387**

[58] Field of Search **D23/387, 386; 285/226, 285/903; 454/65, 63, 903**

[57] **CLAIM**

The ornamental design for a combined extraction and feeding articulated conduit arm unit for gas, as shown.

DESCRIPTION

FIG. 1 is a right side elevational view of the combined extraction and feeding articulated conduit arm unit for gas showing the new design;

FIG. 2 is a left side elevational view of the combined extraction and feeding articulated conduit arm unit for gas;

FIG. 3 is a rear elevational view of the combined extraction and feeding articulated conduit arm unit for gas;

FIG. 4 is a front elevational view of the combined extraction and feeding articulated conduit arm unit for gas;

FIG. 5 is a top plan view of the combined extraction and feeding articulated conduit arm unit for gas; and, FIG. 6 is a bottom plan view of the combined extraction and feeding articulated conduit arm unit for gas.

FIG. 1

FIG. 2

FIG. 4

FIG. 3

FIG. 5

FIG. 6
